BRASSIÈRE

Mack Spetnik, Brooklyn, N. Y., assignor to
 Wolfe & Lang, Inc., New York, N. Y., a corporation of New York

Application November 5, 1948, Serial No. 58,579

7 Claims. (Cl. 2—42)

1

This invention relates to improvements in brassières or bust supports.

An object of the invention is to provide a brassière or bust support which will give firm yet yielding uplift support on both sides of each breast receiving pocket, whereby the breasts of the wearer will be supported in a natural and comfortable position while at the same time restraining the breasts within the confines of the pocket areas.

Another object is to provide a novel bust support garment having a pair of angularly positioned elastic sections on the outside of each breast receiving pocket for exerting uplift pressure on the sides and bottom of the pocket.

A further object of the invention is to provide a brassière with means on the outside of each breast receiving pocket for exerting a greater uplift action on one side of the pocket than on the other.

Still a further object is to provide a bust support garment having on the outside of each pocket a pair of differently dimensioned and angularly positioned elastic sections of substantially triangular configuration for exerting different amounts of uplift action on both sides of each pocket.

A more detailed description of the invention follows, in conjunction with drawings, wherein:

Fig. 1 is an elevational view of the front or outside of the brassière of the invention, shown extended;

Fig. 2 is a section of Fig. 1 taken along the line 2—2; and

Fig. 3 is a perspective view of the front of the garment of the invention, shown on a portion of the body of a wearer.

Referring to the drawings, the bust supporting garment of the invention comprises a pair of breast receiving pockets 10 made of any suitable material, such as non-stretchable satin or rayon. Each pocket consists of upper and lower portions 11 and 13, respectively, stitched together along line 14.

On the outside of each pocket 10 and near the bottom of the lower portion are a pair of elastic segments or sections 16, 18 of substantially triangular configuration. These sections are stitched to each other along line 17, which, if extended, would pass through the center of the pocket, and stitched at the bottom edges 35 to a horizontally stretchable band portion 19. Sections 16 and 18, and band portion 19, are stretchable only in the directions indicated by the bi-directional arrows on the respective materials.

2

One side 31 of triangular section 16 of the left pocket is stitched to side piece 20, while the corresponding side 33 of triangular section 16 of the other pocket is stitched to side piece 22. Side pieces 22 are non-stretchable and made of satin or rayon. It should be noted that although the sides and bottom of the triangular sections 16, 18 are stitched to the garment, the longer sloping edges or sides 15 or 21, respectively, are open and not attached to the pocket 10. This is illustrated clearly in Fig. 2, constituting a sectional view along the line 2—2.

Side piece 22 is attached at that edge which is farthest removed from triangular section 16 to an elastic section 24 terminating in a tab of material 26 provided with suitable eyelets 27. The other side piece 20 is attached by stitching to a strip 25 which is provided with a plurality of hooks 23 adapted to engage the correspondingly positioned eyelets 27 on tab 26.

A pair of shoulder straps 28 are provided, each of which is secured at one end to the top of a breast pocket and extends to one of the side pieces 20 or 22. Each shoulder strap is provided with adjustable means 29.

The length of sloping side 15 of elastic section 16, and the length of sloping side 21 of elastic section 18, are made shorter than the dimensions of that portion of the fabric of the pocket 10 which these edges cover (that is, the portion of the pocket 10 under and adjacent the edges), in order for elastic sections 16 and 18 to exert an upward lift or pressure on the bust when the garment is worn. Elastic section 16 will exert an uplift pressure in the direction shown by arrow A, while elastic section 18 will exert an uplift pressure in the direction shown by arrow B. These pressures along the bottom and sides of the pockets are such as to lift the breast and restrain the same within the confines of the pocket area.

The angular positions of the sloping edge 15 or 21 of the elastic sections 16 and 18 relative to each other for each pocket 10 determine the direction of force indicated by A and B. In the drawings, each sloping edge of the elastic segments is shown positioned at an angle of approximately 45° to the base of the pocket defined by the stitching to the band portion 19. This angle may vary over a wide range.

It is preferred that sloping edges 15 and 21 of elastic sections 16 and 18, respectively, be curved as shown, rather than perfectly straight as in the case of a true triangle, in order to prevent

shirring of the elastic sections when stretched during the wearing of the garment.

In the construction of the brassière shown in the drawings, the edges 31 and 33 of elastic sections 16 have the same lengths, and the bottom edges of these sections joined to band portion 19 are also equal in length. However, the length of sloping edge 21 is longer than the length of sloping edge 15. This difference in lengths of sloping edges 15 and 21 provides greater pull toward the middle part of the garment, thus tending to cause the center of the brassière to hug the flesh between the busts and tending to prevent the junction of pockets 10 from pulling away from the flesh of the wearer, when the garment is subjected to stresses and strains during wear. In practice, the lengths of the sloping edges of the elastic sections 16 and 18 can be made to differ to any desired degree in order to vary the strain or pull which is placed upon the breast within the pocket.

What is claimed is:

1. A body encircling garment having breast receiving pockets, each pocket having on the outside thereof a pair of elastic sections having adjacent edges joined together along a seam which if extended would pass approximately through the center of the pocket, the sections of each pair extending upwardly on opposite sides of the seam at an angle to each other and covering only the lower portion of the pocket near the bottom thereof, the directions of stretch of the elastic sections of each pair being at an angle to each other and such as to exert an uplift pressure on the sides and bottom of the pocket when worn, and an elastic band secured at its top edge to said sections and extending across an area below and over substantially the width of both of said pockets.

2. A body encircling garment having breast receiving pockets, each pocket having on the outside thereof a pair of elastic sections having adjacent edges joined together along a seam which if extended would pass approximately through the center of the pocket, the sections of each pair extending upwardly on opposite sides of the seam at an angle to each other and covering only the lower portion of the pocket near the bottom thereof, the lower edges of said sections of each pair being attached to the bottom of the pocket which they cover, the upper edges of said sections which overlap said pockets being free of attachment to said pockets, the directions of stretch of the elastic sections of each pair being at an angle to each other and such as to exert an uplift pressure on the sides and bottom of the pocket when worn.

3. A brassière having breast receiving pockets, each pocket having on the outside thereof a pair of elastic sections of substantially triangular configuration joined together along a seam which if extended would pass approximately through the center of the pocket, the sloping edges of the sections of each pair extending upwardly from said seam to points oppositely disposed but higher up on the sides of the associated pocket, the sections of each pair covering only the lower portion of the pocket near the bottom thereof, the sloping edges of the sections being shorter than the lengths of those portions of the pocket immediately underneath and extending to the ends of said sloping edges, the bottom edges of each pair of sections being joined to the bottom of pocket, the directions of stretch of the elastic sections being substantially parallel to the sloping edges.

and such as to exert an uplift pressure on the sides and bottom of the pocket.

4. A brassière in accordance with claim 3, characterized in this that said sloping edges are curved away from the center of the pocket.

5. A brassière in accordance with claim 3, characterized in this that said sloping edges are curved away from the center of the pocket, and the sloping edge of one elastic section of a pair is longer than the sloping edge of the other elastic section of the same pair.

15. A body encircling garment having breast receiving pockets, each pocket having on the outside thereof a pair of elastic sections having adjacent edges joined together along a seam which terminates below the center of the pocket but which if extended would pass approximately through the center of the pocket, the sections of each pair extending upwardly on opposite sides of the seam at an angle to each other and covering only the lower portion of the pocket near the bottom thereof, the sloping edges of said sections which extend upwardly from said seam having lengths shorter than the lengths of those portions of the pocket immediately underneath and extending to the ends of said edges, the bottoms of said sections of each pair being attached to the bottom of the pocket which they cover, the directions of stretch of the elastic sections of each 25 pair being at an angle to each other and such as to exert an uplift pressure on the sides and bottom of the pocket when worn, and an elastic band secured at its top edge to said sections and extending across an area below and over substantially the width of both of said pockets.

30. 7. In a brassière, breast pockets each composed of an upper and a lower portion, a pair of substantially triangular shaped elastic sections on the outside of and covering substantially only the bottom and sides of the lower portion of each pocket, the sections for each pocket being stitched together along a vertical seam terminating below the center of the pocket, the bottom edges of the sections being stitched to the bottom horizontal edge of the pocket they cover, the side edges of the sections of each pair being stitched to opposite edges of the pocket, the sloping edges of the triangular-shaped sections extending upwardly from said seam in different directions to points 35 disposed higher up on the side edge of said pocket, said sloping edges being unattached to the pocket between the ends thereof, the directions of stretch of said elastic sections being substantially parallel to the sloping edges, and an elastic band secured at its top edge to said sections and extending across an area below and over substantially the width of both of said pockets.
